UNITED STATES PATENT OFFICE.

FRANCES M. HENNING, OF DOXEY, OKLAHOMA.

CAPPING DEVICE FOR OIL-WELLS.

941,452.

Specification of Letters Patent. Patented Nov. 30, 1909.

Application filed January 31, 1908. Serial No. 413,600.

To all whom it may concern:

Be it known that I, FRANCES M. HENNING, a citizen of the United States, residing at Doxey, in the county of Roger Mills, 5 State of Oklahoma, have invented certain new and useful Improvements in Capping Devices for Oil-WellS; and I do hereby declare the following to be a full, clear, and exact description of the invention, such as 10 will enable others skilled in the art to which it appertains to make and use the same.

In the oil fields, whenever a "gusher" is "struck" during the process of drilling, it is customary to cap the well tubing with 15 a screw cap or plug so as to prevent wasting of the oil or the escape of obnoxious gases. It is customary to employ caps or plugs which are entirely separate from the well tubing but such devices are undesirable in 20asmuch as time must be spent, very frequently in finding them, and it is furthermore quite risky and dangerous for one to attempt a "gusher" owing to the force with which the oil gushes from the tubing and 25 the deadly character of the gases accompanying the oil. In order to expedite the working of oil wells by obviating these undesirable conditions, I have provided a novel form of capping device which is per- 30manently connected to a casing surround- ing the tubing or rather the oil discharge opening and which may be thrown into position to cap the "gusher," by a single work- man, he being protected, owing to the pec- 35ular construction of the device, from the oil and the gases.

In the accompanying drawings, Figure 1 is a view in elevation of the device as asso- 40ciated with an oil well, the cap being thrown back, Fig. 2 is a similar view but showing the cap thrown into position to close the well, Fig. 3 is a vertical sectional view through the device, the cap being in closed position, Fig. 4 is a side elevation of the de- 45 vice, and, Fig. 5 is a top plan-view.

In the drawings, there is shown a length 50 of oil well tubing 7 and a casing 8 which is sunk into the ground, surrounds or in- closes the well tubing, and is cylindrical. This casing is anchored by means of guide 55 rods 9 which are connected at their upper ends to hook shaped lugs 10 formed upon the casing and are anchored in the ground at their lower ends. These guide rods, in addition to holding the casing against up-

ward withdrawal from the ground, hold it in upright position. An oil conducting pipe 11 leads laterally from the casing 8 adjacent the upper end thereof and in this pipe there is interposed a cut-off valve 12.

The casing 8 is formed upon its outer side adjacent its upper end, and at diametrically opposite points with trunnions 13 to which are pivoted the lower ends of links or arms 14. At their upper ends, the arms are 60 formed with slots 15 in which work rectangular lugs 16 which are formed at diametrically opposite points upon the outer periphery of a collar 17 which is of slightly greater diameter than the casing 8 and which is formed concentrically with an opening 18 of a diameter equal to that of the internal diameter of the said casing. The wall of this opening or in other words the inner periphery of the collar is formed with screw 65 threads 19 and the casing 8 is formed at its upper end also with screw threads which are indicated by the numeral 20 and correspond in pitch and direction to the threads 19. It is to be understood that while the 70 collar 17 is normally dropped to the position shown in Fig. 1 of the drawings, it may be swung upwardly from this position to that illustrated in Fig. 2, the inner periphery of the collar registering at such time 75 with the bore of the casing 8. A threaded plug 21 is threaded into the collar and in fact is at all times associated therewith and when the collar has been swung to the position shown in Figs. 2 and 3, the plug is 80 turned by engaging a wrench with a squared head 22 formed upon the upper face of the plug, so as to close the upper open end of the casing 8.

From the foregoing it will be seen that I 95 have provided, in effect, a plug which is supported or carried by a support which may be swung to bring the plug directly above the open upper end of the casing, the plug being adapted to be screwed into the 100 casing to prevent overflow of oil therefrom.

In order that the operator of the device may be protected against squirting of oil and against the outflow of gases directly toward him while capping the casing, the collar is formed with a depending semi-circular flange 23 which forms in effect a hood or apron for the purpose stated.

What is claimed, is:

1. The combination with the outlet tube 110

of an oil well internally threaded at the outer end, of arms swinging from the tube, an internally threaded collar movably coupled to said swinging supports, and a threaded plug engaging the threaded collar and adapted to engage the threaded portion of the tube when rotated.

2. The combination with the outlet tube of an oil well internally threaded at the outer end, of arms swinging from the tube and provided with oppositely disposed guide slots, an internally threaded collar having lugs engaging in said guide slots, and a threaded plug engaging the threaded collar and adapted to engage the threaded portion of the tube when rotated.

3. The combination with the outlet tube of an oil well, of arms pivoted to the tube, a collar loosely carried by the arms, and a plug threaded through the collar and adapted for threaded reception in the end of the tube, the arms being movable to bring the plug into insertible position with respect to the tube.

25 4. The combination with the outlet tube of an oil well, of arms pivoted to the tube, a collar supported between the outer ends of the arms, and a threaded plug threaded

through the collar and adapted for threaded reception in the end of the tube.

5. The combination with the outlet tube of an oil well internally threaded at the outer end, of arms swinging from the tube, a threaded plug engaging the threaded portion of the tube, a threaded collar engaging the threaded plug and provided with a depending flange engaging over the tube, and means for slidably coupling said collar to said swinging arms.

6. The combination with the outlet tube of an oil well internally threaded at the outer end, of arms swinging from the tube and provided with oppositely disposed guide slots, a threaded plug engaging the threaded portion of the tube, a threaded collar engaging the threaded plug and provided with projections slidably engaging in said slots, and a flange depending from the collar and bearing over the tube.

In testimony whereof, I affix my signature, in presence of two witnesses.

FRANCES M. HENNING.

Witnesses:

E. P. GUNN,
J. G. PEEL.
